UNITED STATES PATENT OFFICE.

THOMAS H. EDELBLUTE, OF PITTSBURGH, PENNSYLVANIA.

BLOCK FOR CAR WHEELS.

Application filed June 6, 1923. Serial No. 643,782.

To all whom it may concern:

Be it known that I, THOMAS H. EDELBLUTE, a citizen of the United States, residing at Pittsburgh, in the county of Allegheny and State of Pennsylvania, have invented certain new and useful Improvements in Blocks for Car Wheels, of which the following is a specification.

This invention is for an automatic rail block for car wheels, and is designed particularly for use in mines.

In mining operations, especially coal mining, the workings or rooms leading off from the main headings are, wherever possible, inclined upwardly toward the working face of the room. This is for the purpose of securing drainage from the working face and for enabling full cars to gravitate toward the heading, while only the empty cars need be pushed to the working face. Such inclination of the room floor necessitates that the car is loaded on an incline. The rules of most mines require that a tie or other block be placed under the wheels in addition to the brakes on the car being set.

However, as the labor employed in mines becomes careless as to risks and hazards, and as their aim is centered on getting the cars out as fast as possible, this precaution is disregarded, except perhaps when the mine foreman makes his appearance, accidents, many of them serious, result from an empty or partially loaded car breaking away from the working face.

The present invention has for its principal object to provide an automatic block of a portable nature, which may be advanced with advance of the working face of the room and which enables a car "going to the rise" to pass by it, but which will move back into rail obstructing position when the car has passed and prevent the car from going in the opposite direction until manually operated.

A further object of the invention is to provide a device of this kind which may be readily applied to and removed from a rail, so as to increase its usefulness in temporary positions.

By reason of the portable nature of the device, it is particularly suited for use in rooms and in other temporary positions, and as the advance made in a room each day is but a few feet, the mine foreman can see to it that the device is advanced with the progress of the room. The use of the device is

not confined, however, to the use adjacent the working faces of the various rooms, but the invention may be installed any place in the mine where a device of this nature is required, it being particularly adapted for temporary installation.

A further object is to provide a combination wheel block and derailler.

The present invention also proposes to provide a device of this character which may be cheaply made, has a minimum number of parts, and is well adapted to withstand hard usage, and designed to engage different sized rails turned in different positions.

These and other objects and advantages are obtained by my invention, which may be readily understood by reference to the accompanying drawings, in which:

Fig. 1 is a plan view of one form of my invention applied to a rail in workwise position;

Fig. 2 is a front elevation of the structure shown in Fig. 1, from the down hill side of the device;

Fig. 3 is a section in the plane of line III—III of Fig. 2;

Fig. 4 is a section in the plane of line IV—IV of Fig. 2, showing the manually operable latch;

Fig. 5 is a plan view of a modified structure;

Fig. 6 is a similar view of another modification;

Fig. 7 shows how the invention may be used with a slide rail turned sideways;

Fig. 8 is a similar view, showing the slide rail inverted;

Fig. 9 is a partial plan view of a modification in which the block is designed to function also as a derailler;

Fig. 10 is a section in the plane of line X—X of Fig. 9;

Fig. 11 is an end view of the structure shown in Figs. 9 and 10 from the uphill side;

Fig. 12 is a plan view of still another modification, showing the block member swinging about a horizontal pivot, instead of a vertical one, as in the preceding figures;

Fig. 13 is an end view from the downhill side of the structure shown in Fig. 12;

Fig. 14 is a side view of a similar but slightly modified device.

Referring first to Figs. 1 to 4 inclusive of the drawings, 5 designates a base having a hook portion 6 on its inner end and a verti-

cal stud or pin 7 near its outer end. Formed on the top surface thereof, between the stud and the hook, is an abutment 8 for engaging the outer face of the web of a rail 9, the abutment being undercut to receive the flange 9^a of said rail.

A pin 10 passing through the hook portion 11 serves as a pivot for a cam block 12 having an eccentrically curved inner end 13 for engagement with the inner face of the rail web. The cam plate may be perforated at 13^a to receive a locking pin, not shown.

The curvature of the plate is such that it is driven in an uphill direction into clamping position, so that the strain, which is in a downhill direction, always urges the cam into tighter clamping engagement with the rail.

Extending across the base at a point immediately outward from the abutment 8, is an inclined surface 14, most clearly shown in Fig. 4, which is lowest on the downhill side of the plate.

Pivoted carried on stud 7 is an arm 15 carrying wheel engaging block 16 at its outer end, preferably being formed integrally therewith. This block extends over the top of the rail and its downhill face is transversely curved, as indicated at 17, the block terminating in a narrow edge 18.

The uphill side of the block is concaved, as indicated at 19, to conform substantially to the curvature of a car wheel.

Extending outwardly from each side of the plate, is an arm 20. Each arm 20 has an outer terminal portion 21 which supports opposite ends of an arcuately curved rod 22 that passes through an opening 23 in the pivoting block carrying arm. Surrounding the lower side of the arm is a compression spring 24, and surrounding the rod on its uphill side is a similar spring 25, the springs being balanced so as to urge the pivoted arm to the central position, as shown.

Formed in the uphill side of the arm is a pocket 27, best shown in Fig. 4, having a spring 28 therein that urges latch 29 downwardly, the latch being carried at the end of a rod 30 projecting through the top of the pocket and terminating in an eye 31. The latch has a beveled surface at 32. The latch normally engages against the uphill edge of the plate 5, and prevents the pivoted arm 15 from swinging in a downhill direction, although not interfering with the swinging of the arm in an uphill direction.

In operation, the device is clamped to the rail as close to the working face as convenient. As the cars are pushed toward the working face, the wheels engage the curved surface 17 of block 16, tending to swing the arm 15 in an uphill direction, so that the car can pass by. As soon as the car has been pushed past the device, spring 25, which is compressed when the arm is swung in an up-

hill direction, forces the arm back to normal position, the latch preventing the arm from swinging past central position. The block is thus restored to its position on the track, and the car wheel may rest or come against its concaved uphill side, and be blocked. When the car is being taken down hill, the miner inserts his pick through eye 31 and lifts the latch, whereupon, the weight of the loaded car forces the block to swing off the rail in a downhill direction, letting the car by. After the car has passed, the spring 24 restores the block to position, the latch on the return movement of the arm riding up the inclined surface 14, until it snaps over the uphill edge of the plate.

In Fig. 5, similar reference characters have been used to designate those parts of the device which correspond to the form shown in Fig. 1. In the modification shown in Fig. 5, the swinging arm 15 carries an arcuately curved rod 35 slidably supported on a concentric support 36 and secured to the arm at both ends. The rod moves with the arms, and serves to support springs 37 and 38, corresponding to springs 24 and 25 of the construction in Fig. 1.

In the modification shown in Fig. 5, I have shown a wedge 39 for holding the rail in place instead of the pivoted cam plate 12.

The construction shown in Fig. 6 is generally similar to that hereinbefore described, and similar reference numerals designate the corresponding parts. In this construction, however, the under side of the arm 15 is recessed, as indicated by the dotted lines. A spring 40 in this recess has one end secured to the abutment 8 at 41, and its other end secured to the arm 15 at 42. When the arm is turned in either direction from the central position, the spring is put under tension to urge the arm back to the normal position.

The latch construction as shown in this modification has also been slightly changed. The latch as shown in Fig. 6 comprises an arm 43 pivotally supported at one end by pin 44 and ears 45 on the top of the arm. The other end of the arm has a latch member 46 which projects through an opening 47 in the arm 15. Its principle of operation is similar to the latch described in connection with Fig. 1, but the weight of the latch is utilized in place of a spring to urge it into latching position. The latch may be released by the insertion of a pick or other instrument into notches 48 and 49.

At the working face of the mine it is a common practice to turn the rails comprising the end section of track sideways, or to completely invert the rail, so that it may be slidably laid against the last section of workwise rail and the cars run off from the workwise rail onto the slide rail. Where the rail is turned sideways, the flange of the wheel rides on the web of the rail.

Where the slide rail is inverted, the tread of the wheel rides on the base of the rail.

In Fig. 7, I have shown a modified form of base plate for the stop device, adapted to engage a slide rail turned sideways. The base 50 has a channeled end portion 51 to receive a wedge plate 52 which has a lip 53 for engaging the base of the rail. The abutment 54 has a shoulder 55 to receive the head of the rail, part 56 preferably overhanging the head. The automatic block is not shown, but may be arranged in any of the ways herein described.

Fig. 8 shows a base plate 57 arranged for use where slide rails are inverted. The abutment 58 is undercut at 59 to receive one side of the rail head, and a wedge 60 cut away at 61 driven between the rail and the vertical end portion 62 of the plate 20 holds the rail in position.

In Figs. 9 to 11, I have shown the automatic block in combination with the derailler of the type shown in my co-pending application Serial No. 643,781, filed June 25, 1923.

Mounted at the end of pivoting arm 15 is the block 65 beveled at 66 in order that it may be readily pushed aside by a car going in an uphill direction, that is, in the direction of the arrow in Fig. 9. The uphill side of the block is rounded at 67. Formed on the inside face of the block and set back from the rounded portion 67, is a flanged channel 68, which channel crosses 30 the block. It is so positioned that it will receive the flange of a car wheel if such wheel starts to climb the convex surface 67.

A device of this kind is particularly useful on inclined tracks some distance back 40 from the working face, as well as close to the working face. If a car is coming down the track sufficiently fast that the block will not stop it, that car should be derailed. If the car comes against the block from the 45 uphill side at a reasonable speed, the block 65 will stop and hold it. If, however, the car has such momentum that it climbs the uphill surface of the block, the flanges of the wheels will follow channel 67 and the 50 car will be directed and derailed to one side of the track.

While I have not shown the various spring mechanisms in such detail in Figs. 9 to 11, it will be obvious that I may use 55 springs for operating the arm 15, arranged as described in connection with Fig. 1 or the other figures.

In the modifications shown in Figs. 12 to 14 inclusive, the guard or block swings 60 about a horizontal axis instead of a vertical one.

Referring to the construction shown in Figs. 12 and 13, 70 designates a horizontally bowed base plate having straight portions 71 which provide a seat for the rail,

designated 72. The ends of the plate terminate in rail engaging abutments 73, each abutment having a hole 74 therein to receive a shaft 75. Pivoted to the bowed portion of the plate 70 at 71 is a rail clamping cam 76 having an eccentrically curved surface.

Pivoted on shaft 75 is a block or horn having a hub 77 and a wheel engaging part 78. Part 78 is curved, so that the downhill side thereof does not extend over the rail, while the uphill side 79 lies over the rail when the horn is in a vertical position. This shape of the horn enables the wheel of a car being pushed uphill to engage the curved inner surface of the horn and swing the horn outwardly and downwardly. When the wheel of a car coming down hill hits the edge 79 of the plate, the wheel is blocked.

For yieldably holding the horn or block 78 in a vertical wheel engaging position, I preferably employ a compression spring 80 having one end embracing a stud 82 on the block 78, and the other end surrounding a stud 83 on the base plate.

Surrounding shaft 75 is a coil spring 84 that acts as a cushion to yieldably urge the hub of the block in an uphill direction. When the wheel of a downcoming car strikes the horn, the horn may move longitudinally of the rail against the resistance of spring 84 and thereby absorb the shock of the impact.

In Fig. 14, I have shown a construction very similar to that shown in Figs. 12 and 13, and corresponding reference numerals have been used to designate those parts which are similar. Spring 80 is eliminated, however, and in place of spring 84 is a coil spring 85 having one end engaging the horn and having the other end fixed to a part of the face. This one spring serves both to restore the horn to vertical position and to provide a cushion.

A projection 86 may be formed on the base plate of the various structures to grip into the ground and assist in holding the device against motion in a downhill direction.

While several different forms have been illustrated, it will be seen that they are all relatively small light self-contained structures, suitable for temporary installation and readily portable from one place to another.

Various other changes and modifications than those illustrated may be made in the construction of the device within the contemplation of my invention and under the scope of the appended claims.

What I claim is:

1. A wheel blocking device in the form of a portable unit comprising a base plate, means on the base plate for securing it to the rail, a wheel engaging member carried

on the said plate and movable into and out of wheel engaging position, and means co-acting between the base and the movable member for yieldably urging the wheel engaging member into wheel engaging position.

2. A wheel blocking device comprising a base plate, means on the base plate for securing it to the rail, a wheel engaging member carried on the plate and movable into and out of wheel engaging positions, and means carried by the plate connecting with the wheel engaging member, for yieldably urging the wheel engaging member into wheel engaging position.

3. A wheel blocking device comprising a base plate, means on the base plate for attaching it to a rail, a wheel engaging member carried on the base plate having two wheel engaging surfaces, said wheel engaging member being supported for movement into and out of wheel engaging position, one wheel engaging surface being shaped to provide a wheel obstructing block, the other surface being shaped to cooperate with a wheel to enable a wheel to force the said member out of wheel engaging position, and means for yieldably urging said member to wheel engaging position.

4. A wheel blocking device comprising a base, means on the base for releasably clamping a rail, a wheel engaging member pivotally supported on the base and movable into and out of blocking position, said member having a blocking face on one side, a cam surface for cooperation with a car wheel on the other side, and means carried on the base for urging the wheel engaging member into wheel engaging position.

5. A portable wheel blocking device in the form of a unitary structure comprising a base, means carried by the base for removably clamping it to a rail, a wheel engaging member movable into and out of wheel engaging position carried on the base and arranged to block wheels of cars coming in one direction and to be forced out of wheel engaging position by cars moving in the

opposite direction, and means for yieldably holding the wheel engaging member in wheel engaging position.

6. A wheel blocking device comprising a supporting member, a wheel engaging member movably carried thereby and movable in two directions from a normal position, means for yieldably urging the wheel engaging member to the normal position, and a manually releasable self-closing latch for preventing movement of said wheel engaging member in one direction and out of normal position.

7. A wheel blocking device comprising a supporting member, an arm pivotally mounted thereon, a wheel engaging block on the arm, means for urging the block to a wheel engaging position, said arm and block being movable in an uphill or a downhill direction out of wheel engaging position, and a latch for holding the arm against movement in a downhill direction.

8. A wheel blocking device for use with vehicle rails comprising a base, a wheel engaging member mounted on the base movable into and out of wheel engaging position, means for urging the wheel engaging member to wheel engaging position, one side of the wheel engaging member being adapted to be forced out of wheel engaging position by movement of a wheel thereagainst, the other side of said member being shaped to form a wheel block, and a derailing guide associated with said wheel engaging means for engaging any car wheels which ride up on the block portion thereof.

9. A wheel block comprising a portable base, rail engaging and clamping means on the base, and a wheel engaging and blocking member carried on the base movable out of wheel obstructing position by the passage of a wheel in one direction and blocking a wheel moving in the opposite direction, and means for yieldably maintaining the wheel engaging means in wheel engaging position.

In testimony whereof I affix my signature.

THOMAS H. EDELBLUTE.
